UNITED STATES PATENT OFFICE.

ADOLPH KAHN, OF WASHINGTON, DISTRICT OF COLUMBIA.

EYEGLASSES OR SPECTACLES.

SPECIFICATION forming part of Letters Patent No. 619,578, dated February 14, 1899.

Application filed July 26, 1897. Serial No. 645,994. (No model.)

To all whom it may concern:

Be it known that I, ADOLPH KAHN, a citizen of the United States, residing at Washington, in the District of Columbia, have invented certain new and useful Improvements in Eyeglasses or Spectacles; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention relates to what are known as "frameless" eyeglasses and spectacles, and has for its object to facilitate the fitting of the same and to avoid the liability of breakage; and it consists in the novel features as will be hereinafter more particularly set forth.

Referring to the accompanying drawings, in which the same reference-numeral indicates the same part in each of the views in which it occurs, Figure 1 is a plan view of a pair of eyeglasses embodying my invention. Fig. 2 is a longitudinal sectional view of the same. Fig. 3 is a perspective view of an eyeglass, showing an additional element. Fig. 4 is a longitudinal sectional view of the same. Fig. 5 is a detail view.

Referring more particularly to the drawings, 1 indicates the glass, which may be of any size, thickness, or shape that may be needed by the user. The glass is provided with the usual hole or perforation 2 near the edge of the end that is to be secured to the frame or setting 3. As the glasses required to meet the varied necessities of the users may be thick or thin, concave or convex, and the distance of the hole from the edge may also vary in different glasses, it is necessary that some means be provided by which all these conditions may be met by the ordinary dealer in such articles. If the ordinary two-arm setting be used, then a large stock must be kept constantly on hand to fit all thicknesses of glasses, and with concave glasses it is almost impossible to make a good fit owing to the fact that the tip of the arm must be bent inward toward the glass, which will prevent its passing over the thicker edge. To remedy these objections, resort has been had to a

single arm, to the outer end of which a clamping-screw has been secured after having been passed through the hole in the glass; but experience has shown that the use of such a device is objectionable in that it is difficult of attachment, for the reason that it virtually requires the use of three hands to assemble the parts—one to hold the bridge-piece, one to hold the lens or glass, and the third one to manipulate the screw. As the parts forming the attachment are small and easily broken or lost, this objection is a very serious one, and when it is considered that the point of attachment to the arm is very thin it will be seen that the screw-threads, which must be very fine, will soon be so worn or cut out that they will not hold the parts together. Still another objection to this form of attachment is found in the necessity of fitting the inner end of the glass to the shoulders on the setting to hold it in position. This often necessitates several trials, in which the shoulders must be bent toward or from the glass until they will finally hold the glass against the clamping-screw just tight enough to prevent its movement, without pinching or straining the glass to such an extent as to crack or break it. To make these trials the glass must be secured to the setting and the amount of change in the shoulder estimated and the glass be then removed from the setting and the necessary change made, when the glass must again be secured to the setting, and if the change has not been correct the glass must be again removed and still another attempt be made to get it right; but as the edge of the glass must bear against the shoulders with a slight pressure it is almost impossible to enter the end of the screw into the screw-threaded opening in the end of the arm. And still another objection is found in the liability of breaking the glass in cutting off the end of the screw to correspond with the thickness of the glass, which must be done after it has been passed through the glass or the screw removed after it has been marked. To obviate all of these objections and to produce a device which shall be so simple that any one, although not a mechanic or optician, can fit or remove a glass from its setting at any time without the aid of tools of any kind, I have

constructed the setting with only a single arm or ear, to the outer end of which I have rigidly secured or formed integral therewith a screw-threaded pin or post 4, which can be made of 5 such length as to accommodate any thickness of glass which may be called for by the trade. This pin is located at such a distance from the flexible wings 5, which form the shoulders on the shank of the setting, as will best accommodate 10 the majority of glasses. A nut 6, preferably a wing-nut, is then fitted onto the end of the pin, which will securely clamp the glass against the arm and hold it against displacement. When it is desired to remove the 15 glass, it is only necessary to remove the nut and lift the glass from the pin. In fitting the glass to the setting originally the glass is slipped down over the pin and the amount of change, if any, in the shoulders is noted and 20 the glass removed and the change made to correspond with the variation noted. The glass is then replaced and any further change noted and made without having to apply the nut to the pin. After this fitting has been 25 accomplished, or before, the length of the pin is noted and marked and the glass removed and the end of the pin cut off and smoothed without any danger of breaking the glass, as is liable to happen if the glass be secured by 30 the screw when it is cut off. It also prevents any wear or cutting of the screw-threads by repeated removals of the screw. By giving the screw-threads the proper pitch the strain 35 upon the glasses in placing them upon the nose will have a tendency to tighten the nut and thus prevent its unscrewing—that is, the screw-threads upon the pin at the right eye should be left-handed and the one at the left eye should be right-handed.

40 It has been found by experience that with only a single arm or ear to secure the glasses to the setting, and especially with thick heavy glasses, the arm is liable to bend and throw the glass or lens out of line with the eye. To 45 remedy this objection I have used a supplemental arm or ear 7, one end of which is provided with a hole 8 to fit over the end of the pin 4, while the opposite end may be provided with two legs 9, as shown in Figs. 3, 4, and 5.

50 The legs are made to pass upon opposite sides of the shank outside of the wings 5.

In assembling the parts the arms and pins of the settings are bent to correspond with the surface of the glass, and the legs of the 55 supplemental arms are similarly bent, and when securely fastened together by the single nut employed on each pin it will be found that a very strong and simple attachment

has been secured and one which can be manipulated by any one in any place.

It will be noted from the foregoing that the essential feature of the present invention resides in constructing a setting the shank of which has a single arm, on the end of which is formed an integral threaded pin, over which 60 an apertured lens may be rigidly held without a tightening-nut while the adjustment of the flexible wings on the shank of the setting may be determined upon, after which the lens may be removed and the wings bent, 65 so that when the lens is replaced on the pin the same will be snugly held between the pin and wings and in readiness to be held in such a relation by means of a tightening-nut.

Although I have only shown my invention 70 applied to eyeglasses, it is evident that it can be applied to spectacles as well by having the temple-joints attached to the outer end of the glasses, as shown in dotted lines at 13 in Fig. 1, in the same manner that the settings are attached to the inner end. It is also evident that my invention can be used with any form of bridge-piece and can be made out of any desired material—as gold, 75 silver, aluminium, &c.—and for the thicker 80 glasses the arm of the setting and the pin may be made of extra strength and thickness to prevent the arm from being bent by the heavy load.

Having thus described my invention, I 85 claim—

1. A lens-clamp for eyeglasses, composed of a shank provided with flanges for engaging the edge of the lens, and a flange for engaging one face thereof, said flange having a projection rigidly secured thereto for insertion in a hole in the lens, in combination with detachable means for engaging the said projection and the opposite face of the lens, substantially as described.

2. The combination with a setting for eyeglasses, comprising an arm, the shank of which is provided with flexible wings or shoulders, and the outer end of which is provided with an exteriorly-screw-threaded rigid pin, 95 of a supplemental arm, one end of which engages with the pin and the opposite end is provided with two legs, and a nut upon the end of the pin, substantially as set forth.

In testimony whereof I affix my signature 100 in presence of two witnesses.

ADOLPH KAHN.
